UNITED STATES PATENT OFFICE.

JOHN W. BURGESS AND GEORGE F. BURGESS, OF BROOKFIELD, MISSOURI.

TIRE.

1,001,348.

Specification of Letters Patent. Patented Aug. 22, 1911.

Application filed February 11, 1911. Serial No. 608,030.

To all whom it may concern:

Be it known that we, JOHN W. BURGESS and GEORGE F. BURGESS, citizens of the United States, residing at Brookfield, in the county of Linn, State of Missouri, have invented a new and useful Tire, of which the following is a specification.

It is the object of the present invention to provide an improved tire for vehicle wheels and the invention relates more particularly to that class of tires which embody springs as the cushioning medium and are adapted for disposal upon any ordinary wheel rim.

One feature of the invention resides in forming the device in segments which are adapted to be assembled about the wheel rim. While this broad idea is old in some similar structures, the means for holding the segments assembled, in the instance of the present invention, is novel and presents certain advantages which are to be hereinafter set forth.

A further feature of the invention resides in the novel means provided for arranging and holding the springs in assembled relation upon the segments.

In the accompanying drawings:—Figure 1 is a view partly in side elevation and partly in section of a tire constructed in accordance with the present invention, the same being shown applied to an ordinary vehicle wheel. Fig. 2 is a transverse sectional view. Fig. 3 is a perspective view of one end of one of the segments of the tire.

In the drawings, the tire is illustrated as embodying, primarily, a base comprising a plurality of segments 5 which are preferably in the nature of flat metallic plates adapted to arcuate form, they being adapted for disposal end to end about a wheel rim of the ordinary form. In their outer faces, the segments are formed, each adjacent each lateral edge, with a groove 6 and these grooves register when the segments are

properly assembled and serve a certain purpose to be presently explained. Upon each of the segments there are arranged several of the cushioning elements of the tire and each of these cushioning elements is in the form of a helical spring 7 bowed or arched as clearly shown in the drawings and disposed at its ends against the outer face of

the respective segment 5. Ties, in the form of wires are secured as at 9 to the said outer face of the segment 5 and extend parallel to 55 the adjacent grooves 6, and these wires 8 extend over the end whirls of the springs 7 as clearly shown in Figs. 2 and 3 of the drawings and serve to hold the same firmly to the segment 5. In order to arrest any 60 tendency on the part of the springs 7 to straighten and thereby cause separation of their ends or a lateral stress to be exerted upon the wires 8, the ends of each spring are connected by means of a link which is 65 clearly shown in Fig. 2 of the drawings and is formed from wire bent to form two eyes 10 through which the ends of the spring engage, each link, between its ends, being depressed or bent inwardly toward the segment 5 as at 11. A tie, in the form of a wire 12 is secured to the outer face of each segment between the wires 8 and engages over the depressed portion 11 of the link 10, thus serving to hold the link firmly against the 70 outer face of the respective segment. The tire embodying the present invention further includes a sheath which is fitted over these springs and segments and consists of several layers or plies 13 preferably of some 80 stout material such as leather, water proofed canvas or the like, and a tread layer 14 of leather which leather layer is secured in any suitable manner upon the tread portion of the outermost one of the layers 13. In order 85 to hold the sheath firmly stretched over the springs, and also as a means for holding the segments in assembled relation about the rim, the edges of the sheath or more specifically speaking the edges of the outer of 90 the layers 13 thereof, are fitted into the grooves 6 and wires 15 are then secured in these grooves, the wires serving the functions above noted.

What is claimed is:—

1. A tire consisting of a base, cushioning springs carried by the base, said springs being each of helical form and bowed and secured at its ends to the base, a link connecting the ends of each spring and secured to 100 the base and a casing covering the springs.

2. A tire consisting of a base, cushioning elements carried by the base, each of said elements comprising a spring of helical form

bowed and disposed at its ends against the base, a link connecting the ends of each spring, ties secured upon the base, and holding the ends of the springs thereto, a tie 5 located between the first mentioned ties and secured to the base and extending over the links and holding the same to the base; and a casing covering the springs.

In testimony that we claim the foregoing as our own, we have hereto affixed our signatures in the presence of two witnesses.

JOHN W. BURGESS.
GEORGE F. BURGESS.
